WETTING, CLEANSING, AND EMULSIFYING AGENT

Fritz Günther, Ludwigshafen-on-the-Rhine, Germany, assignor to I. G. Farbenindustrie Aktiengesellschaft, Frankfort-on-the-Main, Germany, a corporation of Germany

No Drawing. Application December 9, 1927, Serial No. 239,003. In Germany December 11, 1926

23 Claims. (Cl. 260—290)

The present invention relates to the manufacture and production of new wetting, cleansing and emulsifying agents.

I have found that products imparting to aqueous liquids excellent wetting, cleansing and emulsifying properties are obtained by mixing an organic acid wetting agent selected from the group consisting of sulfuric acid derivatives of high wetting power, that means true sulfonic acids of high wetting power, or sulfuric acid esters of the nature of Turkey-red oil, and naphthenic acids, with up to equivalent amounts of nitrogen-containing organic bases. Organic sulfonic acids of high wetting power which are to be employed according to the present invention comprise only such acids of which a 0.5 per cent aqueous solution of their sodium salt wets a felt-like textile fabric, for example, of wool or cotton in at the most one hour, but preferably in a much shorter time, for example in a few minutes. Organic sulfonic acids of the said kind which are particularly suitable for the purpose of the present invention are aromatic sulfonic acids containing alkyl-, aralkyl-, cycloalkyl-, or aryl groups, which may, if desired, be further substituted, whether in the nucleus or in the side chain, further sulfonic acids of aliphatic or hydroaromatic compounds, for example the sulfonation products of mineral oils, aliphatic tar oils, naphthenic acids and the like, as well as the known fat-splitting acids, or the ligno-sulfonic acids contained in sulfite-cellulose waste liquor. These acids yield excellent wetting, cleansing and emulsifying agents when treated with organic nitrogen-containing bases in the above specified amounts. As organic bases suitable for preparing the said agents, according to the present invention, aliphatic amines, such as methylamine, or ethylamine, mono-, di-, or triethanolamine, but particularly the heterocyclic nitrogen-containing bases, such as pyridine and its homologues and derivatives, and the like, may be mentioned.

The said components for manufacturing the new products imparting to aqueous liquids a high wetting, cleansing and emulsifying action may be prepared before use by mixing them with each other in the absence of water in up to equivalent amounts, the nitrogenous base being always employed in a substantial quantity, i. e., in a quantity of at least 10 per cent of the equivalent amount, or by preparing them in the form of their salts by working in aqueous solution, or they may be produced only in the liquid or preparation with which they are to be used, by add-

ing the required components thereto. It is to be understood that in the production of the new products no heating or other strong condition of working is applied, since otherwise condensation or other reactions would occur which may lead to the formation of water insoluble products.

When the substances are mixed no heat is applied and the usual reaction of an acid with a base occurs, namely, the formation of a salt corresponding for example to the following equations:

35

The fact that a salt is actually formed is evidenced by the reduction of the acidity of the solutions of the acids when the nitrogenous base desired is added. These salts, moreover, are water-soluble salts since the formation of amides or imides would become obvious by the insolubility of the products.

40

45

It is not essential for the purpose of this invention that the equivalent quantity of the organic nitrogen bases is added to the acids. Even acids which are only partially so saturated exhibit an excellent wetting action. Very useful effects are also obtained with mixed salts prepared by adding to the said acids either several different organic nitrogen bases, or by replacing a portion of the latter by inorganic bases, such as caustic soda, ammonia and the like.

50

55

For preparing aqueous liquids of high wetting and cleansing properties it is generally sufficient to add to the liquids about 0.5 per cent of the said preparations. Aqueous liquids of a higher concentration, however, may also be used. If the said preparations are to be used for preparing highly stable aqueous emulsions or suspensions, or even clear aqueous solutions of sub-

stances insoluble in water, higher concentrations of the preparations are often needed. Also dry compositions of solids, for instance dyestuffs, with the agents according to the present invention may be prepared, which when diluted with water furnish stable suspensions or even clear solutions of the said solids.

The following examples further illustrate the nature of this invention, which however is not restricted to these examples. The parts are by weight.

Example 1

If an acid sulphuric ester of oleic acid, prepared by treating oleic acid with sulfuric acid, 15 be treated with an equivalent amount of caustic soda solution on the one hand and an equivalent amount of pyridine on the other, the aqueous solution, which contains the mixed pyridine and sodium salt of the acid sulphuric ester of oleic acid, 20 displays a far greater capacity for wetting textiles than an equally concentrated aqueous solution of the acid sulphuric ester of oleic acid either neutralized with caustic soda solution or in the free state.

Example 2

To a solution of one part of dibutynaphthalene-sulfonic acid in 200 parts of water, 0.3 part 30 of pyridine is added and the solution is made up to 250 parts with water. The wetting properties of the resulting solution containing the corresponding pyridine salt are considerably better than those of a solution of the free acid or its sodium salt of the same concentration. 35 The corresponding salts of isobutylamine, triethanolamine, or other amines, behave in an equally favorable manner. The dibutynaphthalene-sulfonic acid may be replaced by other sulfonic acids of the character defined, such as those 40 of methyl-, ethyl-, propyl- or also cycloalkyl-substituted organic compounds.

Example 3

An approximately 0.5 per cent solution of a 45 crude gas-oil sulfonic acid, i. e., the sulfonation product of a brown coal tar fraction boiling between 225° and 360° C., in water is treated with the calculated amount of dimethylaniline. The resulting solution containing the salt of the 50 said acid with dimethylaniline possesses excellent wetting properties.

Example 4

To 5 parts of a tri-isopropylbenzenesulfonic 55 acid the equivalent quantity of isobutylamine is added, and the mixture is dissolved in sufficient water to form 1000 parts. The solution containing the corresponding salts has very good wetting properties.

Example 5

2 parts of naphthenic acid are treated with equivalent quantities of either methylamine, 60 isobutylamine, or triethanolamine, and dissolved in sufficient water to form 500 parts. All these 65 solutions containing the corresponding salts exhibit very good wetting properties, substantially more than the corresponding sodium salt.

What I claim is:

1. As, new articles of manufacture wetting, 70 cleansing and emulsifying products comprising a naphthalene sulfonic acid substituted by an alkyl group, and a substantial proportion up to equivalent amounts of an organic nitrogen-containing base selected from the group consisting

of aliphatic amines and monocyclic pyridine bases.

2. As new articles of manufacture wetting, 75 cleansing and emulsifying products comprising a naphthalene sulfonic acid substituted by an alkyl group, and a substantial proportion up to equivalent amounts of a monocyclic pyridine base.

3. As new articles of manufacture wetting, 10 cleansing and emulsifying products comprising a naphthalene sulfonic acid substituted by an alkyl group, and a substantial proportion up to equivalent amounts of pyridine.

4. As new articles of manufacture the salts 15 formed by an organic acid wetting agent selected from the group consisting of organic sulfonic acids and sulfuric esters of high wetting power with an organic nitrogen containing base selected from the group consisting of aliphatic amines and monocyclic pyridine bases.

5. As new articles of manufacture the salts 20 formed by a naphthalene sulfonic acid substituted by an alkyl group, with an organic nitrogen-containing base selected from the group consisting of aliphatic amines and monocyclic pyridine bases.

6. As new articles of manufacture the salts 25 formed by a naphthalene sulfonic acid substituted by an alkyl group, with a monocyclic pyridine base.

7. As new articles of manufacture the salts 30 formed by a naphthalene sulfonic acid substituted by an alkyl group with pyridine.

8. A process of producing wetting, 35 cleansing and emulsifying agents which comprises mixing a wetting agent selected from the group consisting of organic sulfonic acids and sulfuric esters of high wetting power with about equivalent amounts of an organic nitrogen containing base selected from the group consisting of aliphatic amines and monocyclic heterocyclic bases, in which nitrogen is the hetero atom.

9. Wetting, cleansing and emulsifying products 45 comprising an organic acid wetting agent selected from the group consisting of organic sulfonic acids and sulfuric esters of high wetting power and about equivalent amounts of an organic nitrogen containing base selected from the group consisting of aliphatic amines and monocyclic heterocyclic bases in which nitrogen is the hetero atom.

10. As new articles of manufacture wetting, 50 cleansing and emulsifying products comprising a naphthalene sulfonic acid substituted by an alkyl group and about equivalent amounts of an organic nitrogen-containing base selected from the group consisting of aliphatic amines and monocyclic pyridine bases.

11. As a new articles of manufacture wetting, 55 cleansing and emulsifying products comprising a naphthalene sulfonic acid substituted by an alkyl group and about equivalent amounts of a monocyclic pyridine base.

12. As new articles of manufacture wetting, 60 cleansing and emulsifying products comprising a naphthalene sulfonic acid substituted by an alkyl group and about equivalent amounts of pyridine.

13. As new articles of manufacture the salts 65 of alkyl naphthalene sulphonic acids with alkyl amines.

14. As a new articles of manufacture a salt 70 of a dibutyl naphthalene sulphonic acid with triethanol amine.

15. The process of producing a substance 75 which will form a soluble compound with salts

of the alkaline earth of hard waters, consisting in adding ethanolamines to sulphonated oils.

16. A sulphonated oleaginous compound fluidified by an ethanolamine.

6 17. A sulphonated oleaginous compound fluidified by tri-ethanolamine.

18. Wetting, cleansing and emulsifying products essentially comprising an admixture of a monocyclic heterocyclic base in which nitrogen 10 is the hetero atom, and an aromatic sulfo acid, said acid being an acid of high wetting power.

19. Wetting, cleansing and emulsifying products essentially comprising an admixture of a monocyclic heterocyclic base in which nitrogen 15 is the hetero atom and a sulfo acid of the naphthalene group.

20. Wetting, cleansing and emulsifying products essentially comprising an admixture of a monocyclic heterocyclic base in which nitrogen 20 is the hetero atom and a sulfo acid of an aromatic

naphthalene aliphatically substituted in the nucleus.

21. Wetting, cleansing and emulsifying products essentially comprising an admixture of a monocyclic heterocyclic base in which nitrogen 5 is the hetero atom and an alkylated sulfo acid of the naphthalene group.

22. Wetting, cleansing and emulsifying products essentially comprising an admixture of a water-soluble monocyclic heterocyclic base in 10 which nitrogen is the hetero atom and aromatic sulfo acid, said acid being an acid of high wetting power.

23. Wetting, cleansing and emulsifying products essentially comprising an admixture of a 15 sulfo acid of an aromatic poly-nuclear hydrocarbon and a monocyclic heterocyclic base in which nitrogen is the hetero atom, said acid being an acid of high wetting power.

FRITZ GÜNTHER. 20
